Attorney.

UNITED STATES PATENT OFFICE.

FRANK W. SICKLES, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 928,226.

Specification of Letters Patent.

Patented July 13, 1908.

Application filed February 8, 1908. Serial No. 414,902.

To all whom it may concern:

Be it known that I, FRANK W. SICKLES, a citizen of the United States, residing in Hartford, in the county of Hartford and State of Connecticut, have invented certain new and useful Improvements in Type-Writing Machines, of which the following is a specification.

This invention relates to the paper feeding devices of typewriting machines, in which a platen is revolubly mounted in a platen frame, and the paper is fed and guided around the platen by means of spring-pressed rollers, which are thrown into and out of engagement with the platen by means of a key pivoted upon the platen frame.

One object of the invention is to provide improved means for pressing the rollers against the platen. I provide a pair of adjacent roller-supporting arms pivoted upon a rock shaft secured in the platen frame, and springs each secured at one end, the free ends thereof normally bearing against the arms and thereby forcing the rollers against the platen. I also provide improved means for adjusting the tension of the springs.

A further object is to provide improved means for forcing and automatically locking the springs away from the arms. To this end I provide a cam secured upon a rock shaft operable by a key pivoted upon the platen frame, the cam provided with rests or flattened portions to engage the springs and lock them away from the arms.

In the accompanying drawings, Figure 1 is a front elevation of a typewriter platen, paper-feeding rollers and part of the platen frame of an Underwood typewriting machine, showing my improvements. Fig. 2 is a fragmentary perspective bottom view showing the springs locked away from the roller-carrying arms. Fig. 3 is an elevation looking at the right hand end of Fig. 1, but showing the key depressed and the rollers out of engagement with the platen. Fig. 4 is a view similar to Fig. 3 but with the parts in normal positions. Fig. 5 is a detail view showing the springs pressing against the arms.

A platen 1 is revolubly mounted by an axle 2 in the ends 3, 4, of a platen frame. Pivoted upon a rod 5 are pairs of adjacent arms 6, 7, in which are journaled roller-carrying shafts 8, 9, one arm in each pair extending forwardly and upwardly and hav-

ing a depending ear 10, and the other arm extending rearwardly and also having a depending ear 11. The rod 5 extends along the platen and is fixed at its ends in the ends of the platen frame. Brackets 12, secured upon the rod 5, carry a roll-releasing rock-shaft 13, having cams 14, and provided with a crank 15, connected by a link 16 to a lever 17, having a key 18 and pivoted upon the platen frame. A pair of leaf springs 19, 20 are secured upon opposite sides of the brackets 12, and extend inwardly from the ends of the platen frame. Their tips normally engage the ears 10, 11 of the roller-supporting arms, and press them toward each other, thereby forcing the rollers 21, 22 against the platen.

I provide spring-tensioning screws 23, each of which has a head to engage one of the springs, as 19, and a shank threaded through a hole 24 in the opposite spring 20. By turning said screw so as to draw said springs toward each other, the tension thereof is increased.

When the key 18 is depressed, Fig. 3, an upward movement is given to the crank 15 by means of the link 16, rocking the shaft 13 and rotating the cams 14, the latter forcing the springs 19, 20, away from the arms 10, 11, allowing the rollers to drop from the platen. The cams are provided with rests or flattened portions 25, 26 to engage the springs and lock them away from the arms when the key is at the limit of its downward stroke.

Having thus described my invention, I claim:

1. In a typewriting machine, the combination with a platen and a platen frame, of pivoted arms carrying rollers to run upon the platen, said arms having depending ears normally engaged by springs to press them toward each other and thereby cause the rollers to press against the platen, and means for forcing and locking the springs away from the ears to allow the arms with the rollers to drop away from the platen.

2. In a typewriting machine, the combination with a platen and a platen frame, of pivoted arms carrying rollers to run upon the platen, said arms having depending ears normally engaged by springs to press them toward each other and thereby cause the rollers to press against the platen, means for forcing and locking the springs away from

- 2
- the ears to allow the arms with the rollers to drop away from the platen; and means for adjusting the tension of the springs.
3. In a typewriting machine, the combination with a platen frame and a revoluble platen, of pivoted arms carrying rollers to run upon the platen, springs engaging ears depending from said arms, and a key-operated cam engaging the springs and effective to force and lock them away from the ears.
4. In a typewriting machine, the combination with a platen and a platen frame, of pivoted arms supporting rollers to run upon the platen, said arms having members engaged by springs to press the rollers against the platen, and cams operable to release the pressure of the springs on the arms and having rests to engage the springs to lock them in released positions.
5. In a typewriting machine, the combination with a platen frame and a platen, of pivoted arms supporting rollers to run upon the platen, one of said arms extending forwardly and upwardly and having a depending ear, and the other arm extending rearwardly and also having a depending ear, a pair of springs secured at one end and at their free ends engaging the ears to press them toward each other, and a cam operated by a key to force and lock the springs away from the ears.
6. In a typewriting machine, the combination with a platen frame, a platen and rollers running thereon, of adjacent roller-supporting arms pivoted upon a rod secured in the platen frame, the arms having ears engaged by springs to normally press the rollers against the platen, and means for forcing the springs away from the ears and allow the rollers to drop away from the platen.
7. In a typewriting machine, the combination with a platen frame, a platen and rollers running thereon, of adjacent roller-supporting arms pivoted upon a rod secured in the platen frame, the arms having ears engaged by springs and thereby pressing the rollers against the platen, and means for forcing and automatically locking the springs away from the ears.
8. In a typewriting machine, the combination with a platen frame, a platen and rollers running thereon, of roller-carrying arms having depending ears and pivoted upon a rod secured in the platen frame, a rock-shaft having a cam thereon and journaled in brackets secured to the rod, a pair of springs secured each at one end to the brackets and at their free ends normally engaging with said ears, to press them toward each other and thereby cause the rollers to press against the platen, said cams effective to both force and lock the springs away from the ears and allow the rollers to drop away from the platen, and a screw for increasing or decreasing the tension of the springs, said screw having a head to engage one spring and a shank threaded through the other spring.
9. In a typewriting machine, the combination with a revoluble platen and a platen frame, of rolls, arms carrying said rolls, a rock-shaft, a key connected to said rock-shaft, cams upon said rock-shaft, opposite springs pressing said arms and engageable at their tips by said cams, and screws to regulate the tension of the springs, said screws each having a head to engage one spring and a shank threaded through the opposite spring.

FRANK W. SICKLES.
